ASHTRAY FOR CIGARETTES OR CIGARS

Rosalyn Litschgi, St. Louis, Mo.

Application October 8, 1938, Serial No. 233,953

10 Claims. (Cl. 131—240)

This invention relates generally to the art of smokers' articles, and, more particularly to a cigarette, or cigar ash tray.

Among the undesirable properties of the generally employed ashtray, are that they lack a sanitary means for a lighted cigarette or cigar to rest upon, by allowing the accumulation of ashes and moisture on the cigarette or cigar rests, and, it is an object of my present invention to 10 overcome such undesirable features.

An object of the invention is to provide an exceedingly simple and highly efficient ash tray, whereby cigarettes or cigars can be conveniently supported, when not being smoked, in such 15 fashion as to avoid the cigarette paper or cigar wrapper from becoming moistened while at rest.

Another object of the invention is the provision of an ash tray provided with cigarette or cigar rests, which are sanitary in that ashes 20 cannot lodge thereon.

A further object of the invention is the provision of an ash tray having one or more cigarette or cigar supports, and each support being so formed and arranged within a receptacle as to 25 cause a cigarette or cigar to bridge, in an inclined position, a plurality of posts constituting a support therefor.

The novelty and advantageous features of my ash tray will be evident from a consideration 30 of the accompanying drawing forming a part of this specification and illustrating the embodiment of the present invention, and in which similar parts are designated by similar reference characters throughout the several views.

35 In the accompanying drawing:

Fig. 1 is a plan view of an ash tray embodying the features of my invention.

Fig. 2 is a vertical sectional view of one-half of the ash tray taken on a line through one set of 40 cigarette or cigar rests.

Fig. 3 is a vertical sectional view of one-half of the ashtray, taken on a line through the ash receptacle in advance of one set of cigarette or cigar rests and showing the rest in side elevation.

Fig. 4 is a fragmentary view, taken on line 45 4—4 of Fig. 1, looking in direction of the arrows.

Fig. 5 is a fragmentary view, taken on line 5—5 of Fig. 1, looking in direction of the arrows.

50 Fig. 6 is a view similar to Fig. 5, showing one of the cigarette or cigar rests or posts in modified form.

Referring now to the drawing, in detail, it will be seen that the embodiment of the present 55 invention, which has been illustrated in one form

thereof, comprises an open top bowl-shaped body, or receptacle designated, generally, as A, and which is provided, within the same, with a plurality of cigarette or cigar supports or rests, each consisting of a plurality of spaced posts 1, 5 2 and 3, disposed above and adjacent floor ridges or ribs 4, and between the wall 5 of the receptacle and a post 6, which post is shown in the present embodiment of the invention as located within the receptacle and centrally thereof.

10 In the embodiment of the invention shown in Fig. 1, the body or receptacle A is shown as circular in form. The wall 5 is shown as having concaved-convexed inner and outer wall surfaces, although these surfaces can be straight, 15 if so desired, as illustrated in dotted lines in Fig. 3. The receptacle can be of any desired diameter and depth, and it can be made from any desirable material, although the device is illustrated as formed from glass, and, as a unitary article.

The base or floor 7 of the receptacle is shown in Figs. 1, 2 and 4, in one embodiment thereof, as formed to provide a plurality of inclined ridge or rib sections 4, each having a pair of inclined or concaved upper side faces 8, which faces merge to form a ridge line 9 at their upper edges, and, which merge with the upper face of the base or floor 7 of the receptacle A at their lower edges.

30 The interior receptacle space or valley 10 between each ridge or rib section 4 serves as spaced deposit areas within the receptacle to hold ashes and cigarette or cigar stubs.

The floor ridges or ribs 4 are suitably inclined 35 and lead downwardly into the receptacle from near the top of the inner face of the receptacle wall 5. The highest or outer end of each ridge or rib 4 is disposed a suitable distance below upper edges of the wall 5, and, the inner end of 40 each ridge or rib 4 merges with the central post 6, which post 6 projects upwardly and terminates at its upper end in a plane with the upper edge of the wall 5.

The post 6 is provided with a plurality of concaved wall surfaces 11 which merge to form a plurality of perpendicular straight edges 12, which edges are in alignment with the ridge line or edges of the floor ribs 4, as clearly shown in Fig. 1.

45 The posts 1, 2 and 3 together with the upper edge of the wall 5, as shown in Figs. 2 and 3, serve to form supports for cigarettes or cigars to rest upon while not being smoked.

50 The posts 1, 2 and 3 straddle the upwardly 55

projecting ribs 4, and, the posts 1, 2 and 3 are suitably spaced from each other and from the wall 5 and post 6 to form air gaps or spaces 13 therebetween and above the ridges or ribs 4.

5 The ribs 4 are formed integral with the floor of the receptacle A, and, they are arranged in spaced circular fashion and in concentric relation to each other.

The post-like cigarette or cigar rests 1, 2 and 3 10 are shown in the present embodiment of the invention as of different widths and of different heights from the floor of the receptacle A, although they can all be of the same width, if so desired. As illustrated, the post like rests 1 are 15 wider than posts 2, and posts 2 are wider than posts 3.

Each post like rest preferably projects upwardly the same distance above the ridge line of the ribs 4. Each post 1, 2 and 3 has its outer and 20 inner faces at the upper end thereof beveled, as at 14, to form a ridge line seat 15, which ridge line seat is suitably concaved to prevent cigarettes or cigars resting thereon from rolling off of either side thereof and falling into the ash and stub spaces below.

The concaved ridge line seats of the posts 1, 2 and 3 lie in an inclined plane with the upper edge of the wall 5 and they are all of the same distance above the ridge line edge of the floor 30 ribs 4. The upper ends of the posts 1, 2 and 3 being beveled on opposite sides, it will be apparent that cigarette ashes cannot become lodged thereon, as with the present types of cigarette or cigar rests, and that they cannot become moistened while cigarettes or cigars are resting thereon, thus providing sanitary rests for cigarettes and cigars to rest upon when not being smoked.

It will be apparent from Figs. 1, 2 and 3 of the drawing, that when a full length cigarette or 40 cigar is placed to rest on the posts 1, 2 and 3, and the upper edge of the wall 5, that the cigarette or cigar designated B will lie in an inclined position with the upper ends of the posts 1, 2 and 3 merely in point contact with the cigarette or 45 cigar, and with the lighted end of the cigarette or cigar merely in point contact with one of the line edges of the post 6, which serves as an abutment for the lighted end of the cigarette and that by such contacts of the several posts with cigarette or cigar, smothering of the lighted end of the cigarette or cigar is impossible, and, also that sweating of the cigarette or cigar wrappers is impossible as there is full air circulation completely around the same due to the fact that the 55 cigarettes or cigars are supported in distinct elevated positions a sufficient distance away from the floor ribs, or the floor proper, if the floor ribs are not employed, as desired.

When a cigarette or cigar is not full length, as 60 after having been smoked for a while, the same can rest on all three of the post like rests 1, 2 and 3, and if shorter than that, it can rest on the upper edge of the wall 5 and the rest 1, on rests 1 and 2, or upon rests 2 and 3.

65 No matter how a cigarette or cigar is placed on the rests forming the supports, and no matter how long or how short the cigarette may be, it can always be readily removed by taking a hold of the same with the fingers between any pair of post like rests, or post 1 and the wall 5, as there is sufficient space or gap between the posts 1, 2 and 3 and post 1 and the wall 5, as the cigarette or cigar is elevated sufficiently above the 70 ridges of the ribs 4 so that the ribs do not inter-

fer with handling of the cigarette or cigar or interfere with air circulation around the same.

It will be apparent that ashes falling from the lighted end of a cigarette or cigar, will fall by gravity to the upper concaved surfaces of the ribs 5 4 and move downwardly along either or both sides of the ribs to the receptacle space or valley between each pair of ribs. Thus, it will be clearly apparent that ashes cannot lodge upon the upper surfaces of the ribs and that the beveled surfaces 10 of the posts and the ridges upon which a cigarette or cigar lies, will always be clean and sanitary and not coated with ashes to come into contact with a cigarette or cigar supported by the posts 1, 2 and 3.

15 In a modified form of post like rest 1, I have shown in Fig. 6, that the upper surface thereof is convexed, as at 16, instead of concaved, thus, in case a cigarette burns too short, the tendency of the cigarette will be to roll off of the rest, when 20 also supported by the upper edge of the wall 5, and fall into the receptacle to one side or the other of the underlying rib 4.

While I have shown but one arrangement of 25 rests 1, 2 and 3 in the present embodiment of the invention, it is apparent that the particular arrangement of posts 1, 2 and 3 can be modified to change the design of the article without affecting the results attained by the present design. For instance, there may be only one, two or three 30 cigarette or cigar supports, as a whole, instead of four, as illustrated, and, if desired, the ribs 4 can be eliminated altogether.

It is believed that the many advantages of an 35 ashtray constructed in accordance with the present invention will be readily understood, and although the preferred embodiment of the invention is as illustrated and described, it is to be understood that minor changes in the design and details of construction and in the combination 40 and arrangement of parts can be resorted to which fairly fall within the scope of the invention as claimed.

What I claim is:

1. An ashtray comprising a unitary bowl 45 shaped receptacle, said bowl including a side wall, a plurality of spaced upright posts on the floor of the receptacle, said posts being spaced from each other and from the wall with the wall serving as an outer post, the posts being of such 50 heights relative to the height of the wall and to each other as to form an inclined rest adapted to support a cigarette or cigar, bridging the same, and a rib having a sloping wall connecting the posts and disposed below the upper edges of the 55 posts.

2. An ashtray comprising a unitary bowl shaped receptacle, said bowl including a side wall, a plurality of upright posts, said posts being spaced from each other and from the wall with 60 the wall serving as an outer post, the posts being of such heights relative to the height of the wall and to each other as to form inclined rests adapted to support a cigarette or cigar, bridging the same, an additional post spaced from the innermost of the said posts and having a vertical line edge against which the lighted end of a cigarette can rest and a rib having a sloping upper surface extending from the wall to the said additional post below the upper edges of said posts. 65

3. An ashtray comprising a bowl shaped receptacle, a plurality of posts within the receptacle, said posts being spaced from each other and from the wall of the receptacle, the posts being of such heights relative to the height of 70

75

the wall and to each other as to form rests adapted to support a cigarette or cigar, bridging the same, in an inclined position, an additional post spaced from the innermost of the said posts 5 against which the lighted end of a cigarette rests, and an inverted V-shaped rib formed of the floor material of the receptacle and extending from the said additional post to the wall of the receptacle below the said plurality of posts and 10 with the ridge of the rib disposed below the upper edges of said posts and the upper edge of the wall of the receptacle.

4. An ashtray comprising a unitary bowl shaped receptacle including a plurality of posts 15 within the receptacle and spaced from each other at both ends, said posts being spaced from each other and from the wall of the receptacle, an abutment spaced from the innermost post having a line edge against which a cigarette can rest, 20 and a rib having a sloping upper surface below said posts.

5. An ashtray comprising a receptacle having a wall, a plurality of spaced posts having beveled 25 concaved upper edges disposed within the receptacle, said posts being of various heights from the floor of the receptacle and disposed below the upper edge of the wall of the receptacle and adapted to support a cigarette or cigar on the beveled edges thereof in an inclined position, 30 and an abutment having a line edge against which the lighted end of a cigarette or cigar can rest.

6. An ashtray comprising a bowl shaped receptacle, a post within the receptacle, a plurality 35 of cigarette or cigar rests disposed within the receptacle, said rests being spaced from each other and from the wall of the receptacle and the post therein, and said posts being of such heights relative to the height of the wall of the receptacle 40 and to each other as to support a cigarette or cigar, bridging the same, in an inclined position, and an inclined ridge having sloping sides below the upper ends of the rests free from contact with a cigarette or cigar.

7. An ashtray and rest for lighted cigarettes or cigars comprising a receptacle, a post within the receptacle so fashioned as to provide a plurality of perpendicular edges against which the lighted ends of cigarettes or cigars can rest without 45 smothering the lighted end thereof, the upper end of the post being of a height equal to the height of the wall of the receptacle, there being a

plurality of concentrically arranged posts within the receptacle, the posts being of different heights below the height of the wall of the receptacle, the upper ends of the posts being beveled to provide ridges for cigarettes and cigars to rest upon, and said ridges being concaved. 5

8. A device of the class described comprising a bowl shaped body, an upright post within the body having a longitudinally fluted peripheral face to provide perpendicular abutment ridges, 10 said post projecting upwardly with its upper face in a plane with the upper edge of the wall of the receptacle, a plurality of spaced circularly and concentrically arranged post like rests within the receptacle to form a plurality of cigarette or 15 cigar supports cooperating with the upper edge of the wall of the receptacle and the said upright post, said circularly and concentrically arranged posts being of different heights below the height of the wall of the receptacle to hold a cigarette 20 or cigar at rest in inclined position.

9. A device of the class described comprising a bowl shaped body, an upright post within the body having a longitudinally fluted peripheral face to provide perpendicular abutment ridges, 25 said post projecting upwardly with its upper face in a plane with the upper edge of the wall of the receptacle, a plurality of spaced circularly and concentrically arranged post like rests within the receptacle to form a plurality of cigarette or cigar 30 supports cooperating with the upper edge of the wall of the receptacle and the said upright post, said circularly and concentrically arranged posts being of different heights below the height of the wall of the receptacle to hold a cigarette 35 or cigar at rest in inclined position, there being inverted V-shaped ribs formed from the bottom material of the receptacle below the upper ends of the posts, and the upper edges of the circularly and concentrically arranged posts being beveled 40 and concaved.

10. In combination with a bowl like receptacle, a plurality of spaced upright post like members disposed within the receptacle and integral with the floor thereof, an abutment spaced from the 45 innermost post having a line edge against which a cigarette can rest, and a floor rib connecting the posts with the abutment and providing a sloping surface below the upper edges of the posts. 50

RODALYN LITSCHGI.
